WINDING DEVICE

Norman Schiff, Franklin Park, N.J., assignor to Johnson & Johnson, a corporation of New Jersey

Filed Sept. 21, 1960, Ser. No. 57,451

6 Claims. (Cl. 242—75.51)

This invention relates to a mechanism and method for winding a web of sheet material having little body and which deforms readily as by wrinkling even under slight tension. Winding is accomplished in a way such that in the finished roll the material is devoid of wrinkles and has good edge alignment as between its various convolutions.

Wrinkles formed by the application of tension in material of this type will, if allowed to remain in the web as it is wound up, become permanent creases and render the material unfit for its intended use. Furthermore, if such a web is kept under tension at all times during the winding operation, its extreme lack of rigidity will render ineffective the use of guiding devices which apply pressure to the edge of the web in order to locate it appropriately.

In accordance with the invention web material is wound upon a reel mounted on a spindle. As the spindle rotates to effect the windup operation it necessarily imparts some tension to the web which forms longitudinal wrinkles to which reference has just been made. At a given phase in each revolution of the windup spindle, the windup torque exerted thereon is interrupted and the spindle freed. During this period of interruption, devices associated with the spindle cause it to reverse its rotation for a fraction of a revolution to render the material in the outer convolution of the wound up roll loose and devoid of tension. Since permanent deformation has not taken place, removal of tension has the effect of allowing the loose material in the outer convolution to return to its normal unwrinkled state. When windup torque is again applied, the spindle resumes rotation in a normal direction and the loose material is first wound up under substantially no tension until it lies flat on the underlying convolution before any substantial tension is again exerted in the web to pull it along from the source of material from which it is obtained.

Obviously too, when a web of such material is longitudinally wrinkled under tension, its width from edge to edge will have been reduced and, if the wrinkles are wound into the web, registration of the edges of the various convolutions one with another will be absent. However, if the windup reel is equipped with edge guide means they will, when the web assumes its normal width upon release of tension, serve appropriately to position the edges of the web during the take-up of the loop and prior to the continued exertion of tension as the windup operation proceeds.

A better understanding of the invention may be had by reference to the accompanying drawings wherein:

FIG. 1 is a perspective view of a machine equipped with the present improvements, parts of the machine being cut away to expose its operating parts;

FIG. 2 is a perspective view of part of the machine shown in FIG. 1, but at a different phase in its cycle of operation;

FIGS. 3, 4, 5 and 6 illustrate diagrammatically the formation and dissipation of looseness in the web material during different phases of a windup cycle; and

FIG. 7 is a wiring diagram better to illustrate operation of certain of the parts.

A roll of material 10 having a tendency to deform longitudinally into wrinkles upon application of longitudinal tension is supported on a spindle 11 fixed in the near side member of the machine frame and from which

2

the material in the form of a web 12 is unwound as it travels forward through the machine to and through a mechanism 13 which may perform any suitable and desired operation on the web (FIG. 1). From this mechanism the web 12 advances at constant linear speed through the machine under the influence of a pair of closely spaced pull rolls 14, 15 mounted one above the other on parallel shafts 16, 17 transverse to the web's travel and which engage the web, one from above and the other from below. The parallel shafts 16, 17 are journaled for rotation in the near side frame member of the machine and a chain driven sprocket 18 on the lower shaft drives both the rolls in opposite directions to advance the web through the medium of a pair of meshing pinions 19, 20 fixed one on each of said shafts.

The web 12 passes up and partially around the top pull roll 15 and then in an S path between it and an overlying idler roll 21 mounted for rotation on a transverse shaft 22 fixed in the machine frame.

From the idler roll 21 the web 12 advances at controlled speed as determined by the speed of rotation of the pull rolls 14, 15, to a windup reel 23 fixed on and against relative rotation with respect to a transverse windup shaft 24 journaled at one position along its length in the near side frame member of the machine. The windup shaft is connected through a magnetic clutch 25 whose casing has a fixed support in the machine frame with another shaft 26 in axial alignment with the windup shaft and which likewise is journaled for rotation in the far side frame member of the machine. A sprocket 27 fixed on this shaft is driven by a chain 28 from a sprocket 29 fixed on the same shaft 17 which, it will be recalled, accommodates the top one of the pull rolls which is instrumental in controlling the speed of travel of the web through the machine. The windup shaft thus has a common drive with the pull rolls.

The ratio of the sprockets 27, 29 is such that the shaft 26, when the magnetic clutch is energized, tends always to drive the windup reel at a speed in excess of that permitted by the pull roll controls and consequently at a speed which always exerts tension on the traveling web during the windup operation. However, since the magnetic clutch 25 is a "slip" clutch, the slippage which takes place permits the speed of the windup shaft 24 to accommodate itself to the increasing diameter of the roll on the real windup. The tension in the web 12 which results from the tendency of the magnetic clutch to overdrive, a tendency which results from the need to accommodate the increase in the diameter of the windup roll, is the cause of the wrinkles in the web and of the reduction in its width under tension. In the absence of a mechanism such as that herein described, wrinkles could be wound permanently into the roll to render it useless for its intended purpose.

The magnetic clutch 25 may be of any appropriate variety and, by way of example, that may be used which is sold under the trademark "Magneclutch" by Vickers Electric Division of Vickers Inc. St. Louis, Missouri, and illustrated in Bulletin No. 6000-A, 11-53, and in Supplement No. 1 of that bulletin, published by that company. The magnetic clutch is energized from a source of D.C. current to which reference is made hereinafter. Switch contacts 30 in the D.C. current circuit effect a driving connection to the windup shaft 24 by energizing the magnetic clutch 25 when the switch is closed and disestablishes the driving connection when the switch is open. Opening and closing of the switch may be under the control of a rotatable edge cam 31 having high and low portions, and driven from a timing motor 32. In the particular embodiment shown, the normal position of the switch, i.e., when the cam is at rest, is its closed

position, and this occurs when the switch arm engages a high portion of the cam.

The switch control edge cam 31 is cycled by the timing motor 32 arranged upon inauguration of its cycle to rotate the cam through one revolution. As the cam starts its rotation, a switch arm 33 which carries one of the switch contacts 30, drops from a high portion thereof, in which position the electric circuit to the magnetic clutch is closed, to a low portion thereof, in which position the electric circuit to the magnetic clutch is opened. As the cam continues its rotation the switch arm 33 again moves up on a high portion of the cam to re-establish the electric circuit through the magnetic clutch, whereupon the cam continues its rotation back to normal position where it automatically comes to rest as the timing motor 32 completes its cycle of operation. Driving torque through the clutch is interrupted when its energizing circuit is disestablished.

The timing motor 32 is in an electric energizing circuit having a control switch 34 whose instantaneous operation inaugurates cycling operation of the timing motor as will be described in more detail hereinafter, and the switch itself is operated by a crank arm 35 fixed on the rewind shaft 24 and whose weight causes it normally to hang in a vertical position when driving torque through the magnetic clutch has been interrupted.

Assume now that the electric circuit through the magnetic clutch is closed and that the crank arm 35 is starting to move upwardly in the direction of the arrow (FIGS. 1 and 3) from its lower-most position after having completed a revolution during which tension has produced wrinkles in the web as a result of the material's inability to resist deformation. At this phase of the cycle the switch control cam 31 is at rest with its switch contacts 30 in closed position. After crank arm 35 has moved upwardly about sixty degrees (60°) from its lower-most position (the dot and dash line position in FIG. 3), the switch 34 in the timing motor circuit is operated by engagement therewith of the lower end of the crank arm thus to inaugurate operation of the timing motor. As the timing motor 32 starts and rotation of the edge cam 31 initiated, the switch arm 33 drops from a high portion of the edge cam to a low portion thereof so as thereby to open the electric circuit through the magnetic clutch and interrupt transmission of torque thereby. When the electric circuit through the magnetic clutch is disestablished, the crank arm 35 will have rotated clockwise upwardly somewhat beyond the sixty degree (60°) position where the switch was engaged or to about ninety degrees (90°) from the vertical (i.e., the dot and dash line position shown in FIG. 4). As the driving torque through the clutch is interrupted, the crank arm 35 under the force of gravity drops back to vertical position as from the dot and dash line position in FIG. 5 to the solid line position shown in both FIGS. 2 and 5. This action of the crank arm causes the windup reel 23 to rotate in a direction counter to its normal direction of rotation, thereby tending to unwind the web and form looseness therein. Since at the same time there is no tendency for the idler roll 21 to pull back on the web, the looseness would be evidenced by formation of a free loop 36 in the web beyond the point where the advancing web is tangent to the windup roll or by formation of slack in advance of such point or both. In any event all tension in the web is eliminated other than that caused by weight of material in the loop or the slackened off portion (FIGS. 2 and 5).

While the crank arm 35 is dropping back to vertical position, the switch contacts 30 in the circuit to the magnetic clutch remain open although the timing motor 34 continues to operate. However, as the crank arm reaches its vertical position or after approximately one-half second from the time the torque transmitted by the clutch was interrupted, a high portion of the edge cam 31 again engages the switch arm 33 to close the contacts 30 and re-establish the circuit through the magnetic clutch. This

causes rotation of the windup shaft 24 in its original direction and at a speed faster than when the feed of the web is normal since now the tension on the web 12 has been removed and there is no substantial slip in the clutch. As this windup operation is inaugurated, that portion of the web 12 which shall have formed the loop 36 or the slack in the web will be the first material rewound on the windup reel. This material is substantially in tensionless condition, i.e., as previously stated the tension is no more than that due to the weight of the material in the loop or slack and, since this is negligible, the tension in the web during this windup operation is such that the material will lie flat in the rewound convolution and devoid of all wrinkles.

The windup reel 23 is equipped at its opposite ends with opposed radially extending flange elements 37 which serve by engagement with the opposite edges of the web to cause the edges of adjacent convolutions to be laid down in registry. These flange elements of course will fail to function properly when the web is under such tension as to cause it to shrink in width to a dimension less than the distance between flanges. However, when the web is under no tension and is being rewound with the loop as the source of material, the web will have again assumed its full width and the flange members then will act to perform their intended function.

As the crank arm 35 starts up from its depending vertical position to initiate rewinding of the web, it again engages the switch 34 in the timing motor circuit; but, since the timing motor 32 at this time has not completed its operating cycle, such engagement of the arm with the switch has no effect and the windup shaft continues its windup operation. The windup operation continues even after the cycle of the timing motor has been completed or until the crank arm again completes a full revolution and again engages the switch which inaugurates operation of the timing motor cycle. After completion of the fast windup of the slack material, from the loop or otherwise, during which time the web is substantially devoid of tension and because of which the convolution rewound lies flat on and in edge registry with the underlying convolution, the speed of wind again is controlled by the feed rolls 14, 15 which results in the wrinkle forming tension.

A better understanding of the electrical controls may be had from the circuit diagram of FIG. 7. A motor 38 for driving the pull rolls 14, 15 and, consequently, the drive shaft 26 to the clutch is connected across main leads L1, L2 and the operation of starting and stopping the motor is controlled in any suitable manner as by a motor switch 39. Also connected across main leads L1, L2 is a relay 40 whose winding 41 is included in a circuit comprising the crank operated switch 34 and a parallel holding circuit which includes contacts 42 which close to render the holding circuit operable when relay 40 is initially energized by the crank operated switch 34. Operation of the crank operated switch is momentary only but upon its opening the relay 40 nevertheless remains energized by virtue of its holding circuit.

Operation of relay 40 also closes a pair of contacts 43 which connects the timing motor across the main leads L1, L2 and inaugurates its cycle of operation. The timing motor is geared to drive the edge cam 31 whose periphery is engaged by the switch arm 33 which may be spring held in contact with the cam and which in its normal position, i.e., when in contact with the high portion of the cam, causes its contacts 30 to close an electrical circuit through the magnetic clutch 25, as previously described, and through a rectifier 44 across the main leads. The rectifier furnishes the D.C. current. As operation of the timing motor is inaugurated, switch arm 33 rides off the high portion of cam 31 to open the circuit through the magnetic clutch. This circuit remains open for reasons previously described until switch arm 33 again engages the high portion of cam 31, whereupon the circuit through the magnetic clutch again is established, and

this circuit remains established for so long as the switch arm 33 continues on the high portion of the cam back to its normal position and for so long also as the cam then remains at rest. Normally closed contacts 45 in the relay holding circuit are momentarily opened near the conclusion of the timing motor cycle. This acts to break the relay holding circuit with consequent disengagement of the contacts 42 which were established upon operation of the switch 34 initially closed by the movement of the crank arm 35, and the parts are then ready for the next cycle of operation of the machine. As previously stated, closing of the crank arm operated switch 34 by upward movement of the crank arm immediately after it has dropped back to vertical position with de-energization of the magnetic clutch, has no effect because at that time the holding circuit through the relay 40 remains operative.

A suitable timing motor, magnetic controls therefor, and cam controlled switch operated thereby are available on the market. One such suitable device is a Series RC single cycle multi-cam timer described in Bulletin No. 200 which together with operating instruction sheets for such timers are published by Industrial Timer Corporation of Newark, New Jersey.

The invention has been described in connection with one embodiment thereof only and many modifications are included within its spirit. The invention therefore is to be limited only by the scope of the pending claims.

What is claimed is:

1. A windup device for a traveling web of sheet material which comprises: a source from which the traveling web of sheet material is delivered at a controlled speed, means including a windup shaft on which the traveling web of sheet material is wound, devices for applying torque to the windup shaft tending to rotate the shaft in one direction to wind up the material at a speed greater than the controlled speed, and means including devices for periodically interrupting the application of said torque and for applying said torque again after a controlled period of interruption, said last mentioned means including also instrumentalities for reversing the rotation of said shaft during said period of interruption.

2. A windup device for traveling web of sheet material which comprises: a source from which the traveling web of sheet material is delivered at controlled speed, means including a windup shaft on which the traveling web of sheet material is wound, devices including a slip clutch adapted when engaged to transmit torque to the windup shaft tending to rotate the shaft in one direction to wind up the material at a speed greater than the controlled speed, and means including devices for periodically disengaging the clutch to interrupt transmission of said torque and for re-engaging the clutch again after a controlled period of interruption, said last mentioned means including also instrumentalities for reversing rotation of said shaft during the period when the clutch is disengaged.

3. A windup device for a traveling web of sheet material which comprises: a source from which the traveling web of sheet material is delivered at controlled speed, means including a windup shaft on which the traveling web of sheet material is wound in convolutions, devices including a slip clutch adapted when engaged to transmit torque to the windup shaft tending to wind up the web of sheet material in one direction at a speed greater than its controlled speed of delivery, and when disengaged to interrupt transmission of torque to the windup shaft, means for disengaging and re-energizing the clutch once during the winding of each convolution of web material, and instrumentalities for reversing rotation of the shaft during the period when the clutch is disengaged whereby substantially tension-free material is made available in the traveling web from which web material is rewound upon the roll upon re-engagement of the clutch.

4. A windup device for a traveling web of sheet ma-

terial which comprises a source from which the traveling web of sheet material is delivered at controlled speed, means including a windup shaft on which the traveling web of sheet material is wound, devices including a slip clutch adapted when engaged to transmit torque to the windup shaft tending to wind up the web of sheet material in one direction at a speed greater than its controlled speed of delivery, and when disengaged to interrupt transmission of torque to the windup shaft, means controlled from the windup shaft for disengaging and re-engaging the clutch once during the winding of each convolution of web material, and instrumentalities including a weighted crank arm for effecting a reverse movement of the windup shaft through a portion of a revolution during the period when the clutch is disengaged whereby substantially tension-free material is made available in the traveling web from which web material is rewound upon the roll upon reengagement of the clutch.

5. A windup device for a traveling web of sheet material which comprises a source from which the traveling web of sheet material is delivered at controlled speed, means including a windup shaft on which the traveling web of sheet material is wound, devices including a magnetic clutch adapted when energized to transmit torque to the windup shaft tending to wind up the web of sheet material in one direction at a speed greater than its controlled speed of delivery and when de-energized to interrupt transmission of torque to the windup shaft, a circuit containing the magnetic clutch together with a switch operable to control energization and de-energization of the clutch, a timing device associated with the switch for determining the period the clutch is de-energized and having a cycle of operation inaugurated under the control of the windup shaft, and means associated with the shaft for effecting reverse rotation of the shaft during the period the clutch is de-energized whereby substantially tension-free material is made available in the last wound convolution of web material from which the web material is rewound upon the roll when the magnetic clutch is re-energized.

6. A windup device for a traveling web of sheet material which comprises a source from which the traveling web of sheet material is delivered at controlled speed, means including a windup shaft on which the traveling web of sheet material is wound, devices including a magnetic clutch adapted when energized to transmit torque to the windup shaft tending to wind up the web of sheet material in one direction at a speed greater than its controlled speed of delivery and when de-energized to interrupt transmission of torque to the windup shaft, a circuit containing the magnetic clutch together with a switch operable to control energization and de-energization of the clutch, a timing device associated with the switch for determining the period the clutch is de-energized and having a cycle of operation inaugurated under the control of the windup shaft, means associated with the shaft for effecting reverse rotation thereof during the period the clutch is de-energized whereby substantially tension-free material is made available in the last wound convolution of web material from which the web material is rewound upon the roll when the magnetic clutch again is re-energized, and a common drive shaft for the source from which the traveling web of sheet material is delivered to the windup device and from which torque for rotating the windup shaft is delivered through the magnetic clutch.
